DESIGN FOR A SHEET CLAMP

George Yates, Glendale, Calif.

Application November 2, 1942, Serial No. 108,682

Term of patent 14 years

To all whom it may concern:

Be it known that I, George Yates, a citizen of the United States, residing at 530 Riverdale Drive, Glendale, California, have invented a new, original, and ornamental Design for a Sheet Clamp, of which the following is a specification, reference being had to the accompanying drawing, forming part thereof.

Referring to the drawing:

Figure 1 is a side elevation of a sheet clamp, showing my new design;

Figure 2 is a top plan view of the device of Figure 1; and,

Figure 3 is an end view of the device of Figure 1.

I claim:

The ornamental design for a sheet clamp, as shown.

GEORGE YATES.
